US0D1092414S

(12) **United States Design Patent** (10) **Patent No.:** **US D1,092,414 S**
(45) **Date of Patent:** **** Sep. 9, 2025**

(54) **WIRELESS REMOTE CONTROLLER**

- (71) Applicant: **Buster and Punch Limited**,
Peterborough (GB)
- (72) Inventor: **Massimo Buster Minale**, London (GB)
- (73) Assignee: **Buster and Punch Limited**,
Peterborough (GB)
- (**) Term: **15 Years**
- (21) Appl. No.: **29/923,290**
- (22) Filed: **Dec. 28, 2023**

(30) **Foreign Application Priority Data**

(57) **CLAIM**

The ornamental design for a wireless remote controller, as shown and described.

DESCRIPTION

FIG. 1 is a top-front-left perspective view of the wireless remote controller, according to a first embodiment;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top-front-left perspective view of the wireless remote controller, according to a second embodiment;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the drawings depict portions of the wireless remote controller that form no part of the claimed design.

1 Claim, 14 Drawing Sheets
